(57) **CLAIM**

The ornamental design for a tablet holder, as shown and described.

DESCRIPTION

FIG. 1 is a front and top perspective view of a first embodiment of a tablet holder, showing my new design; FIG. 2 is a back and bottom perspective view thereof; FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a top view thereof, showing the unfolded status;

FIG. 10 is a front perspective view of a second embodiment of the tablet holder;

FIG. 11 is a back and bottom perspective view thereof;

FIG. 12 is a front view thereof;

FIG. 13 is a back view thereof;

FIG. 14 is a left side view thereof;

FIG. 15 is a right side view thereof;

FIG. 16 is a top view thereof;

FIG. 17 is a bottom view thereof; and,

FIG. 18 is a top view thereof, showing the unfolded status.

The broken lines in the figures illustrate portions of the tablet holder that form no part of the claimed design.
